UNITED STATES PATENT OFFICE.

JOSEPH BLAIR, OF PHILADELPHIA, PENNSYLVANIA.

DESIGN FOR A CURTAIN FABRIC.

SPECIFICATION forming part of Design No. 16,034, dated April 7, 1885.

Application filed March 2, 1885. Term of patent 3½ years.

To all whom it may concern:

Be it known that I, JOSEPH BLAIR, a citizen of the United States, residing at Philadelphia, in the county of Philadelphia and State of Pennsylvania, have invented and produced a new and original Design for a Curtain Fabric; and I do hereby declare that the photographic print accompanying this specification conveys to any one skilled in the art a clear understanding of the same, and is sufficient to enable such person to use my invention.

The leading features of my design consist, first, in the representation at A of flowers, leaves, and branches, these, with the ornamental guards and cross-stripes at top and bot-

tom, representing an ornamental cross-border for a curtain fabric; second, the representation at B of flowers, buds, leaves, and branches, with the ornamental guards and cross-stripes at top and bottom. The lower guard, D, shows a representation of a knotted fringe. These combined represent an ornamental dado for a curtain fabric.

I claim as my invention and desire to secure by Letters Patent—

The design for a curtain fabric, as shown and described.

JOSEPH BLAIR.
